CUTTER CHAIN

William W. Sloane, Chicago, Ill., assignor to
Goodman Manufacturing Company, Chicago,
Ill., a corporation of Illinois

Application October 11, 1944, Serial No. 558,123

4 Claims. (Cl. 262—33)

This invention relates to improvements in cutter chains for kerf-cutting machines, and has as its principal objects to provide a novel and improved form of cutter chain so arranged as to minimize wear on the parts of the chain and to provide sprocket tooth bearing for each link of the chain without decreasing the strength of the chain.

Another object of my invention is to provide a new and improved cutter chain having a novel form of means for detachably holding the bits of the chain in their respective chain blocks.

Other objects of my invention will appear from time to time as the following specification proceeds and with reference to the accompanying drawing wherein:

Figure 1 is a plan view of a cutter chain arranged to cut a horizontal kerf, showing the chain passing around its drive sprocket, with certain parts of one of the bit carrying blocks of the cutter chain broken away and certain other parts thereof shown in horizontal section;

Figure 2 is a view in side elevation of the cutter chain with certain parts broken away and certain other parts shown in substantially longitudinal section;

Figure 3 is a transverse sectional view taken through one of the bit carrying blocks of the cutter chain and showing the cutter bar about which the chain travels, in transverse section;

Figure 4 is a fragmentary horizontal sectional view taken substantially along line 4—4 of Figure 3;

Figure 5 is a sectional view taken substantially along line 5—5 of Figure 1; and

Figure 6 is an end view of the cutter chain showing the cutter chain guided in its cutter bar and showing the various positions of several blocks and cutter bits of the chain.

Referring now to the drawing the cutter chain shown is an endless chain including a plurality of cutter bit carrying blocks 10, 10 pivotally connected together by links 11, 11 and having cutter bits 12, 12 held in position therein in bit holders 13, 13, mounted in sockets 14, 14 formed in a body portion 15 of each of said blocks.

Each cutter bit carrying block is of a substantially U-shaped formation and includes the bit carrying body portion 15, which has a pair of parallel spaced side plates 17, 17 extending inwardly therefrom and herein shown as being formed integrally therewith. Said body portions of different bit carrying blocks of the chain are arranged at different angles in a well known manner, so that the several bits of the chain may

completely cut a kerf of sufficient width to cut clearance for a cutter bar 18, about which said cutter chain is guided. Said cutter bar may be of any well known form so is not herein shown or described in detail.

Each side plate 17 is provided with a longitudinal gib 19 extending along its inner end, which is adapted to engage a gibbed guide 20 formed in the cutter bar 18, to retain said cutter chain 10 within said bar as it travels thereabout. Said side plates and gibs also have an arcuately formed recessed inner end 21, which is formed to conform to the form of the curved forward end of the cutter bar, to enable the chain to freely travel around said cutter bar.

The bit carrying body portion 15 of each chain block 10 extends laterally beyond the side plates 17, 17 and has inner shouldered portions 23, 23, which, as herein shown, extend to the outer margins of the cutter bar 18. Said shouldered portions are adapted to have bearing engagement with the outer side of said cutter bar and cooperate with the gibs 19, 19, to aid in holding said cutter chain in parallel relation with respect to the outer side of said cutter bar during travel of said chain about said cutter bar, and thus to reduce wear on said cutter bar and chain.

The bit holder 13 includes a bit receiving member 25 and a bit clamping member 26 having interengaging connection therewith. Said bit receiving member has an advance face which is inclined at the angle of the bit and is adapted to be abutted by the back surface of the bit, and has parallel spaced sides extending along opposite sides of the bit. Said bit receiving member has a head 29, on the outside of said body portion, which serves to limit inward movement of said member with respect to the socket 14 and which also serves to back up the portion of said bit 40 which extends outside of said block. Said bit receiving member has a tongue 30 projecting forwardly from its inner end, which is adapted to extend within a slot 31 formed in the clamping member 26, to retain said clamping member in the proper position in said block to receive the cutter bit when initially inserted therein, and to prevent the separation of said clamping member from said bit receiving member, when the cutter bit has been removed from said bit holder.

The clamping member 26 has a rear face which is adapted to engage the lower end of the advance face of the cutter bit 12, and which is held in engagement therewith by means of a set screw 33 threaded in the advance end of said bit carrying body portion and engaging a portion 34 of

said clamping member, which extends a slight distance within the aperture through which said set screw is threaded. A retaining screw 35, threaded in the end of said bit carrying body portion opposite from the set screw 33, is adapted to engage a rear slotted portion 36 of said bit receiving member, to positively hold said bit receiving member within the cutter chain block, and to prevent said bit receiving member and said clamping member from being thrown from the block, during cutting, and in cases where the cutter chain bits may be broken off or where said clamping member was not initially tightened sufficiently to prevent said bits from being thrown from said bit clamping member.

A simplified form of bit holding member has thus been provided to retain the cutter bit 12 within its bit receiving block, which is positively held within its block by a retaining screw threaded through one end of said block and which is clamped to the bit to positively hold the bit within said bit clamping member by means of a set screw threaded in the opposite end of said block.

The bit receiving sockets 14, 14 in the blocks 10, 10, which are inclined at the different angles with respect to the side plates of said block in the different blocks of the chain, to position the cutter bits to cut a kerf in the coal face sufficiently wide to admit the cutter bar 18, are also so arranged that their lower portions come to one side or the other of the space between the side plates 17, 17. This keeps the inner ends of the bit holders 13, 13 out of the space between the insides of said side plates, and provides an unimpaired sprocket tooth receiving recess between each of said side plates, and also provides an opening in the lower end of said socket for ready access to each bit holder and cutter bit therefor. The various blocks of the chain when assembled may form a pattern somewhat similar to that shown in Figure 6, and are so positioned that no bit receiving socket extends within the space between said side plates and that certain of the bits are to one side of the center line of the chain and certain other of the bits are at the opposite side of said center line so that the bits are all substantially evenly spaced to completely cut out the coal from the upper to lower end of the kerf, when the cutter chain is cutting in a horizontal plane.

The links 11, 11 each include a pair of parallel spaced straps 37, 37 connected together by shouldered connecting sleeves 39, 39 (see Figure 5). Each of said sleeves, as herein shown, has a bearing portion in the space between said parallel spaced straps, which is adapted to be received in the space between adjacent teeth of a cutter chain drive sprocket 40 and which is also adapted to be engaged by said adjacent sprocket teeth, so that each of said sleeves is driven by a sprocket tooth, to provide a more efficient and positive means for driving the chain from its sprocket than formerly, without sacrificing strength of the chain.

The parallel spaced side straps 37, 37 and their shouldered sleeves 39, 39 extend in the space between the side plates 17, 17 of the chain blocks 10, 10, and are pivotally connected thereto by means of bushings 41, 41 extending through said shouldered sleeves and through said side plates. Locking pins 43, 43 extend through the centers of said bushings and have bent-over ends 44, 44, which extend within slots 45 and 46 formed in the ends of said bushings and said side straps, respectively, to lock said bushings from turning movement with respect to said side plates, so said

bushings may form bearing members for said shouldered sleeves 39, 39.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a cutter chain and in combination with a drive sprocket therefor, a plurality of bit carrying links, each of said links having a bit carrying body portion having a plurality of parallel spaced side plates extending inwardly therefrom, each of said body portions being apertured to receive a cutter bit and said apertured portions being so arranged as to maintain said bit at the proper cutting angle and out of the space between said side plates, to provide an uninterrupted space between said side plates, and means for pivotally connecting said links together so as to provide sprocket tooth bearing on each link of the chain including a pair of parallel spaced links, sleeve for connecting said links together adjacent their opposite ends, said links being adapted to extend in the space between said side plates and said sleeves being adapted to provide sprocket tooth bearing for the links of said chain, a separate bushing extending through each of said sleeves and opposite of said side plates, and means connected with said bushings, to connect the links of the chain together and to hold said bushings from rotation with respect to said side plates, so said bushings may form bearings for said sleeves.
2. In a cutter chain and in combination with a drive sprocket therefor, a plurality of bit carrying links, each of said links having a bit carrying body portion having a plurality of parallel spaced side plates extending inwardly therefrom, each of said body portions being apertured to receive a cutter bit and said apertured portions being so arranged as to maintain said bit at the proper cutting angle and out of the space between said side plates, to provide an uninterrupted space between said side plates, and means for pivotally connecting said links together so as to provide sprocket tooth bearing on each link of the chain including a pair of parallel spaced links, sleeves for connecting said links together adjacent their opposite ends, said links being adapted to extend in the space between said side plates, and said sleeves being adapted to provide sprocket tooth bearing for the links of said chain, a separate bushing extending through each of said sleeves and opposite of said side plates, and a pin for locking said bushings to said side plates, to hold said bushings from rotation and to connect the links of said chain together so said bushings may form pivotal bearings for said sleeves.
3. In a cutter chain and in combination with a cutter bar having a channelled guide within which the cutter chain is guided, a sprocket for driving said cutter chain about said cutter bar, said chain including a plurality of bit carrying links having a bit carrying body portion having a cutter bit detachably mounted therein and having parallel spaced side plates extending inwardly therefrom, said side plates each having a longitudinal gib on its inner end, to retain said links within the guides of said cutter bar, and having longitudinally extending shouldered por-

tions at their outer ends which are adapted to have bearing engagement with the outer side of said cutter bar, said bit carrying body portions of said links each having a bit receiving socket and said body portions being arranged at different angles for different bit carrying links of the chain so as to maintain each bit at the proper cutting angle, and said body portions and sockets being arranged to keep the inner end of each bit cut of the space between said side plates in each different position of said bits in the several bit carrying links of said chain, to provide an uninterrupted sprocket tooth receiving space between said side plates, and means for connecting said links together so as to provide sprocket tooth bearing on each link of the chain including a pair of parallel spaced links, sleeves extending through opposite ends of said links, for connecting said links together, each of said sleeves providing a sprocket tooth bearing surface so a sprocket tooth may engage each link of the chain, and means extending through said sleeves and said side plates, forming a bearing surface for said sleeves and connecting the links of the chain together.

4. In a cutter chain and in combination with a cutter bar having a channelled guide within which the cutter chain is guided, a sprocket for driving said cutter chain about said cutter bar, said chain including a plurality of bit carrying links having a bit carrying body portion with parallel spaced side plates extending inwardly therefrom, certain of said bit carrying body por-

tions extending at different angles with respect to said side plates to hold the cutter bits at angles sufficient to cut clearance for the entire chain and cutter bar, and said body portions each having a bit receiving socket formed therein and spaced to one side of the space between said side plates, to maintain said bits at the proper cutting angle and to keep their inner ends out of the space between said side plates in each different position of the several bits, to provide an uninterrupted sprocket tooth receiving space between said side plates, said side plates having longitudinal gibs on their inner ends adapted to retain said links within the guides of said cutter bar and said body portions extending laterally from said side plates and having inner shouldered portions adapted to have bearing engagement with the outer side of said cutter bar, and means for connecting said links of said chain together so as to provide sprocket tooth bearing on each link of the chain including a pair of parallel spaced links having sleeves extending through opposite ends thereof, each of said sleeves providing sprocket tooth bearing so a sprocket tooth may engage each link of the chain, a separate bushing extending through each of said sleeves and said side plates of said chain, and means for locking said bushings to said side plates and for holding them from rotation with respect thereto so said bushings may form pivotal bearings for said sleeves.

WILLIAM W. SLOANE.
